PIEZOELECTRIC TRANSDUCER

John P. Arndt, Jr., Euclid, Ohio, assignor to The
Brush Development Company, Cleveland, Ohio,
a corporation of Ohio

Application January 11, 1943, Serial No. 471,966

16 Claims. (Cl. 171—327)

1

This invention relates to piezoelectric transducers and, more particularly, to transducers of the general type constituted by a plurality of sections of crystalline piezoelectrical material that are joined together to form a composite element which either bends, expands or contracts, twists, or otherwise deforms when subjected to electric potentials.

Previous to the invention, a number of methods had been proposed for joining to each other the pre-electroded major faces of a plurality of crystal sections and for providing a conductive, externally extending lead for the inner electrodes. One method that has achieved great commercial success is explained in the United States patent to A. L. W. Williams, No. 2,106,143.

In accordance with the teaching of the Williams patent, a multiplate flexing element, for example, is fabricated from two plates cut from a homogeneous Rochelle salt crystal, each of which carries upon at least one of its major faces an electrode comprising colloidal graphite. The electroded faces are cemented together with a lead extension, formed of thin metal, clamped between them. The cementing is a manual operation, inasmuch as each assembly must be treated individually, and the labor cost, naturally, is somewhat high.

One successful cement that has been employed is Rochelle salt, melted in its own water of crystallization. However, it is expensive and, furthermore, it is somewhat difficult to handle.

Accordingly, an object of this invention is to provide an improved method of manufacturing a piezoelectric transducer of the multiplate type, whereby the number of manual operations shall be minimized and the labor cost, accordingly, diminished.

Another object is to provide a method of manufacturing transducers, of the type described, whereby a more uniform product shall be obtained.

Another object is to provide a method of the type described that may be practiced through the utilization of automatic machinery.

Another object is to provide an improved method of fabricating a piezoelectric transducer, of the type described, whereby an electroded crystal section may be provided with a conductive lead extension and, simultaneously, be joined to a similar section at a single operation.

Another object is to provide a method for manufacturing multiplate transducers from Rochelle salt sections or the like.

A still further object of the invention is to pro-

2

vide a method for manufacturing piezoelectric transducers from crystalline materials having dielectric constants lower than that of Rochelle salt.

5 Briefly, in accordance with the invention, instead of employing cement for the purpose of joining together the pre-electroded faces of a plurality of crystal sections, the said faces are caused to adhere to the opposite surfaces of a ribbon or strip of metallic foil or the like, through the action of heat and pressure upon a coating of material such as wax or the like, or a synthetic plastic, with which the ribbon has been supplied. The coating may be applied mechanically to the 10 ribbon, thus obviating the manual step of applying cement to the electroded faces of the sections. Furthermore, the application of heat and pressure to the ribbon may be accomplished by automatic or semi-automatic machinery and 15 continuous production can thus be obtained.

Conductive contact between the surface electrodes of the sections and the ribbon may be assured by incorporating finely granulated conductive material, such as silver or the like, into 20 the surface coatings of the ribbon or by roughening the surface of the ribbon as by providing it with integral struck-out projections or teeth.

The heating may be accomplished inductively 25 or by passing an electric current, either alternating or unidirectional, directly through the foil from an appropriate source.

The novel features considered characteristic 30 of the invention are set forth with particularity in the appended claims. The invention itself, however, both as to its organization and its method of operation, together with additional objects and advantages thereof, will be fully apparent 35 from the following description of certain specific embodiments thereof, when read in connection with the accompanying drawings, wherein:

40 Figure 1 is a view, partly perspective and partly diagrammatic, exemplifying the method of the invention.

45 Figure 2 is a plan view of a strip of metal foil, or ribbon, having surface coatings of a material that softens under the influence of heat, to which finely divided conductive particles have been added;

50 Figure 3 is a side view, in vertical section, of the ribbon taken along a line corresponding to the line III—III in Figure 2;

55 Figure 4 is a plan view of a strip of metal foil provided with integral protuberances adapted to project through the surface coatings for the pur-

pose of conductively connecting the foil to the electroded surfaces of the crystal sections;

Figure 5 is a side view, in vertical section, of the ribbon, taken along a line corresponding to the line V—V in Figure 4;

Figure 6 is a conventionalized plan view exemplifying the adaptation of the improved method to continuous production of multiplate piezoelectric transducers;

Figure 7 is a side view of the apparatus shown in Figure 6, and

Figure 8 is a vertical sectional view, taken along a line corresponding to the line VIII—VIII in Figure 6.

In the drawings, no attempt has been made at dimensional accuracy; they are to be considered solely as suggestive and explanatory of the method to be followed and not as views of actual transducers or apparatus. Equivalent elements, in all figures, are similarly designated.

Referring now to Figure 1 of the drawings, one embodiment of the method, shorn of non-essential steps, comprises first forming a stack or "sandwich," so to speak, from a lower section 1 of piezoelectric material, a similar upper section 3 and an intermediate strip 5 of metallic foil or the like which carries an upper coating 7 and a lower coating (not shown) of material that softens and becomes "tacky" under the influence of heat but which is substantially rigid after cooling. The major faces of the crystal sections, including the two that are in contact with the surface layers on the foil, carry electrodes of colloidal graphite or the like, previously applied thereto by employing the method disclosed in the Williams patent aforementioned, or they may carry metalliferous electrodes deposited thermionically by cathode disintegration or mechanically by a process such as the Shoop spray.

A multiplicity of metallic particles, preferably angular, may be intermingled with the surface coatings on the foil, as shown in Figures 2 and 3, or the foil itself may be roughened, or be furnished with a plurality of integral, struck-out projections 11 as shown in Figures 4 and 5.

After the stack has been assembled, the temperature of the metal foil is next raised sufficiently to cause softening of the surface coatings thereon and pressure, indicated by the arrow in Figure 1, is applied for the purpose of squeezing out any surplus coating material and of causing the metallic particles, or the integral projections carried by the foil, to establish conductive connection between the foil and substantially the entire electroded surface of each section.

In order to heat the foil, it may be connected to an appropriate potential source 9, alternating or unidirectional, through a circuit comprising master switch 11, a rheostat 13, an automatic time switch 15 and an ammeter 17. The rheostat, ammeter and time switch are for the purpose of enabling limitation of the current to such a value and for such a pre-determined time period that the piezoelectric properties of the crystal sections shall not be injuriously affected.

It is difficult to give specific values for the current necessary to soften the coating material and cause its adherence to the electroded crystal sections, or to state the time required. Those factors can be determined only by experiment, inasmuch as they depend upon the particular coating material employed, upon the dimensions of the sections and upon the particular piezoelectric material. With Rochelle salt sections, it is best not to exceed a temperature for the foil

that will raise the temperature of the crystal sections to over 130° Fahrenheit; primary ammonium phosphate and certain other phosphates isomorphous therewith can stand much higher temperatures without damage.

As to the coating material itself, good results have been obtained with a mixture of one part beeswax, one part battery sealing compound, and two parts rosin, and it is to be expected that synthetic materials, either thermoplastic or thermosetting, workable at temperatures below or near that at which the piezoelectric sections are injured, will eventually become available if not already in confidential use.

When the mentioned compound is employed as the coating material an extremely strong bond between the foil and the crystal sections is secured, and one that does not appreciably deteriorate even though the transducer is kept in operation over long periods of time.

Lead extensions, of course, may be applied also to the outer faces of the multiplate flexing element by following the method outlined herein.

In the event that an intermediate lead is not required to extend from the transducer, the protruding ends of the foil may be severed after the assembly has cooled and the coating material has solidified. Also, as will be obvious, there is no limit to the number of sections that may be stacked up and provided with lead extensions according to the method disclosed herein.

Should it be desired to adapt the improved method to continuous production, still further minimizing the labor cost, apparatus may be provided for automatically heating the lead extensions. For example, as shown in Figures 6, 7, and 8, a moving carrier 19 may be employed, such as a traveling belt or the like which slides over the surface of a fixed support 21 and which is provided with a plurality of longitudinally aligned pockets 23, each dimensioned to accommodate a stack of crystal sections.

As the belt moves past a first location, designated A in Figure 6, an operator places a plurality of crystal sections, interleaved with coated foil, in each empty pocket, seeing to it that the extremities of the foils 5 extend upwardly and outwardly from the pockets to lie flat upon the surface of the belt at the opposite ends of the stack. The stack of sections and lead extensions may be built up in the pockets by the operator, or previously assembled stacks, held together by rubber bands or other suitable means, may be inserted in them.

Suitable means, exemplified by the weights designated W in Figures 7 and 8, may be provided for retaining the stacks in their respective pockets until after the heating operation.

As the belt moves from the left toward the right the ends of the foil may be caused to engage flexible contact members or rollers 25, disposed in the path of travel of the pockets, to apply momentarily a potential thereto from an appropriate source 27. The cooled assemblies may be removed thereafter from the belt by another operator, or they may be permitted to drop off into a suitable bin 29 or the like.

Motion of the belt may be continuous or intermittent and means (not shown) may be employed for moving the contact members 25 into and out of engagement with the foil-extremities, as they pass, if desired. Either alternatively or simultaneously with the heating by conduction the foils may be heated inductively by disposing a coil 31 of copper tubing or strap, supplied from

a suitable source 33 of high frequency potential, adjacent to the path of movement of the belt, as shown in Figure 7.

For some applications, a transducer constituted by a plurality of sections of crystalline material, having a much lower dielectric constant than that of Rochelle salt, such as a primary phosphate, gives satisfactory results. In transducers of that type, the pre-electroding of the opposed surfaces may be dispensed with and the lead extensions themselves may serve as electrodes. The presence of a thin layer of wax or the like, devoid of metallic particles, between the crystal face and the lead extension, is not objectionable.

From the foregoing, it will be obvious that the disclosed method marks a decided advance in the fabrication of piezoelectric transducers of the multiplate type. Because of the consolidation of several steps, formerly necessary, into a single operation, the new method enables a material reduction in the labor cost and, in addition, the transducers produced thereby have extremely uniform electrical characteristics.

Although several alternative embodiments of the invention have been illustrated and described, the inventor is fully aware of the fact that many modifications thereof will be at once apparent to those skilled in the art. The invention, therefore, is not to be restricted except insofar as is necessitated by the prior art and by the spirit of the appended claims.

What is claimed is:

1. The steps in a method of fabricating a piezoelectric transducer which comprise selecting a section of piezoelectric material a face of which has an electrically conductive layer, applying to said face a conductive lead-extension having a surface coating of material capable of adhering to the conductive layer when subjected to heat and pressure, subjecting said surface to heat and pressure and simultaneously establishing a plurality of electrically conductive paths between said extension and said layer.

2. The steps in a method of fabricating transducer elements from at least two sections of crystalline piezoelectric material each of which has an extended substantially planar face, that comprise placing a layer of electrically conductive material upon each of said extended faces, disposing between said faces an extended conductive lead-in element each surface of which has a coating of material that softens under the influence of heat and pressure, urging said sections toward each other to exert pressure on said coatings, heating said lead-in element to a temperature sufficiently high to cause softening of said coatings and concurrently establishing a multiplicity of conductive paths between the layers of conductive material and the lead-in element.

3. The method as defined in claim 2, characterized in this: that heating of the lead-in element is accomplished by causing an electric current to flow therein.

4. The method as defined in claim 2, characterized in this: that heating of the lead-in element is accomplished inductively.

5. The steps in a method of fabricating transducer elements from at least two sections of crystalline piezoelectric material each of which has an extended substantially planar face, that comprises disposing between said faces an extended foil-like electrode each surface of which has a coating of material that softens under the influence of heat, urging said sections toward each other to exert pressure on said electrode, heating

said electrode to a temperature sufficiently high to cause softening of said coatings and thereafter cooling the assembly to the temperature at which the coating material becomes substantially rigid.

5. In a method of fabricating a piezoelectric transducer the steps which comprise selecting a section of piezoelectric material, electroding a face of the section of piezoelectric material, applying to the electroded face of said piezoelectric material electrical conductor means capable of adhering thereto when subjected to heat and pressure, subjecting said electrical conductor means to heat and pressure sufficient to cause the said electroded face and the conductor means to approach sufficiently close to each other to establish a plurality of electrically conductive paths between said conductor means and the electroded face of said piezoelectric material, and thereafter cooling said electrical conductor means to cause 15 said conductor means to adhere to said piezoelectric material.

6. The method as set forth in claim 5 further characterized in this: that heating of the adhesive material is accomplished by causing an electric current to flow in the conductive lead-extension.

7. The method as set forth in claim 1 further characterized in this: that heating of the adhesive material is accomplished by inductively causing an electric current to flow in the conductive lead-extension.

8. The method as set forth in claim 1 further characterized in this: that heating of the adhesive material is accomplished by inductively connecting leads to the conductive lead-extension and by means of the leads passing electric current through said conductive lead-extension.

9. The method as set forth in claim 1 further characterized in this: that heating of the adhesive material is accomplished by electrically connecting 35 leads to the conductive lead-extension and by means of the leads passing electric current through said conductive lead-extension.

10. The method as set forth in claim 5 further characterized in this: that heating of the coating material is accomplished by causing an electric current to flow in the foil-like electrode.

11. The method as set forth in claim 5 further characterized in this: that heating of the coating material is accomplished by inductively causing 45 an electric current to flow in the foil-like electrode.

12. The method as set forth in claim 5 further characterized in this: that heating of the coating material is accomplished by electrically connecting 50 leads to the foil-like electrode and by means of the leads passing electric current through said foil-like electrode.

13. The invention as set forth in claim 6 further characterized in this: that heating of the electrical conductor means is accomplished by causing an electric current to flow in the electrical conductor means.

14. The invention as set forth in claim 6 further characterized in this: that heating of the 60 electrical conductor means is accomplished by inductively causing an electric current to flow in the electrical conductor means.

15. The invention as set forth in claim 6 further characterized in this: that heating of the electrical conductor means is accomplished by 65 electrically connecting leads to the conductor means and passing electric current through the said conductor means.

16. In a piezo crystalline multiplate assembly, 70 a first plate, electrode means on a surface of said first plate and in intimate electrical contact therewith, a second plate, electrode means on a surface of said second plate and in intimate electrical contact therewith, and electrically conductive sheet means having adhesive means on each

surface thereof connecting said first and said second plates together with their electrode surfaces in face-to-face relationship, said sheet means including a plurality of integral electrically conductive portions extending at angles to the plane of said sheet, said integral portions extending through said adhesive means and making electrical contact between said sheet and the said surface electrode means on said first and said second plates of piezoelectric material.
